(57) CLAIM

The ornamental design for a carrier for plant starter pots, as shown and described.

DESCRIPTION

FIG. 1 is an upper perspective view of a carrier for plant starter pots shown in accordance with our new design;

FIG. 2 is a top plan view thereof;

FIG. 3 is a bottom plan view thereof;

FIG. 4 is a side elevational view thereof, the opposite side being a mirror image thereof; and,

FIG. 5 is an end elevational view thereof, the opposite end being a mirror image thereof.

Throughout the figures broken line showings are for illustrative purposes only and form no part of the claimed design.
